(57) **CLAIM**

The ornamental design for a coil component, as shown and described.

DESCRIPTION

FIG. 1 is a front elevation view of a first embodiment of a coil component, showing our new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a top, front, left side perspective view thereof; and

FIG. 8 is a bottom, front, left side perspective view thereof.

FIG. 9 is a front elevation view of a second embodiment of a coil component, showing our new design;

FIG. 10 is a rear elevation view thereof;

FIG. 11 is a right side elevation view thereof;

FIG. 12 is a left side elevation view thereof;

FIG. 13 is a top plan view thereof;

FIG. 14 is a bottom plan view thereof;

FIG. 15 is a top, front, left side perspective view thereof;

and,

FIG. 16 is a bottom, front, left side perspective view thereof.

The equal-length broken lines in the drawings depict portions of the coil component that form no part of the claimed design.
